UNITED STATES PATENT OFFICE.

RUSSEL T. WALDREP, OF TIFTON, GEORGIA.

RAILWAY-SWITCH FROG.

SPECIFICATION forming part of Letters Patent No. 529,983, dated November 27, 1894.

Application filed July 2, 1894. Serial No. 516,367. (No model.)

To all whom it may concern:

Be it known that I, RUSSEL T. WALDREP, a citizen of the United States, residing at Tifton, in the county of Berrien and State of Georgia, have invented certain new and useful Improvements in Railway-Switch Frogs; and I do hereby declare the following to be a full, clear, and exact description of the invention, such as will enable others skilled in the art to which it appertains to make and use the same.

My invention relates to improvements in railway switch-frogs and it consists in certain novel features hereinafter described and claimed.

Reference is had to the accompanying drawings, wherein the same parts are indicated by the same letters throughout the several views.

Figure 1 represents a plan view of a portion of the track and siding, the switch being set for the main line. Fig. 2 represents a section along the line $y-y$ of Fig. 1, and looking toward the top of the sheet. Fig. 3 represents a plan view of the improved switch-frog in which the switch is set for the siding. Fig. 4 represents a section along the line $x-x$ of Fig. 3, and looking to the left. Fig. 5 represents an inverted perspective view of the movable rail, and Fig. 6 represents a perspective view of the chair plate as detached from the rail.

A and A' represent the rails of the main line.

B and B' represent the rails of the siding, the rail B, being connected to the continuation B² thereof, by means of the short rail B³, chair plate C, and the movable rail D. The rails B and B² are mounted at an incline on the blocks b, as shown in Fig. 2, while the upper end of the rail B² rests on the block b' to which the frog-rail D is pivotally attached. The short rail B³ is connected to the rail B in the usual way, and has its opposite end tapering as shown, the web of the said tapering end engaging in the groove c, beneath the overhanging lip c', and the vertical face c⁰ of the chair plate C, the cut away edge of the rail fitting snugly against the edge of this vertical wall c⁰, as shown most clearly in Fig. 1.

The inside of the chair plate is curved as at c² and c³ to fit snugly against the side of the main line rail A'. The outside of the

chair plate is provided with a flange or rib c⁵ having bolt holes c⁶ for securing the same to the cross-ties. It will thus be seen that the chair plate C forms a strong and secure support for the end of the short rail B³.

The frog rail D is provided with a straight face d, which forms a continuation of the edge of the siding rail, when the switch is set for the siding, which edge is bent outward as at d' near the free end of the frog rail, and is finally curved outward as at d², so as to avoid the possibility of being an obstruction when set for the main line. The said frog rail is in the form of a rail near its pivoted end, which is cut away in an inclined direction as shown at d³ in Fig. 5, which inclined portion fits snugly against the rail A' when the switch is set for the siding. The free end of the frog rail is broad and flat as shown at Fig. 5, and is provided with a lug d⁴ to which the end f of the rod F is pivotally connected. The frog rail is also provided with lugs d⁵ and d⁶ which slide along the tops of the blocks E' and E, and which rest on the said blocks when the device is set for the siding. The inner end of the frog rail rests on the blocks b' and E², all of which blocks are firmly secured to the tops of the ties. The block E is cut away as at e to allow the flanges of the car wheels to pass when the switch is set for the main line.

The rod F is operated by the crank h on the shaft H, which shaft is revolved by a connection with any suitable switch stand or other apparatus designed for the purpose.

It will be noticed that when the switch is set for the main line as shown in Fig. 1, the main line is not broken, and hence with the herein described frog, there is no necessity for breaking the main line.

When the switch is set for the siding, as shown in Figs. 3 and 4, the frog rail D rests on top of the main rail A' and is also supported by the blocks E, E', E² and b', while the edge d' is braced against the rail B³, and the edge d² is braced against the rail A'. Moreover, the novel construction of the chair plate C gives a firm support to the tapered end of the rails B³. Thus it will be seen that the herein described device affords adequate protection and support to those parts of the frog rail and the siding rail that are gener-

ally broken or injured in frogs of somewhat similar construction. These and various other advantages of the herein described construction will be readily understood by anyone skilled in the art.

Having thus described my invention, what I claim, and desire to secure by Letters Patent of the United States, is—

In an apparatus of the character described, 10 the combination with one of the main line rails and the blocks E and E' of a pivoted frog rail adapted to swing partly over said main line rail, and provided with a straight edge d sloping outward as at d', curved outward as at d², and provided with flat lugs d⁵ and d⁶ adapted to rest on said blocks and give an enlarged supporting surface; a siding rail 15 cut away at an angle and projecting above

the level of said main line rail; and adapted to bear against said sloping edge d' of the 20 frog rail; and a chair plate C approximately triangular in form having the projection c² fitting snugly against the web of the main line rail, with a groove c dovetailed at c' adapted to receive the flange of the cut away 25 siding rail; a vertical face c⁰ adapted to support the cut away side of the siding rail, and a flange c⁵ with bolt holes c⁶ therein for securing said chair plate to the cross ties, substantially as and for the purposes described. 30

In testimony whereof I affix my signature in presence of two witnesses.

RUSSEL T. WALDREP.
